(57) **CLAIM**

The ornamental design for the portable digital camera with touch sensitive sketch screen, as shown and described.

DESCRIPTION

FIG. 1 is a bottom and rear perspective view of the portable digital camera with touch sensitive sketch screen showing our new design;

FIG. 2 is a top and rear perspective view thereof;

FIG. 3 is a top and front perspective view thereof;

FIG. 4 is rear elevational view thereof; showing a user's hand using the camera button;

FIG. 5 is rear elevational view thereof showing a user's hand using the stylus;

FIG. 6 is a bottom edge elevational view thereof;

FIG. 7 is a left side elevational view thereof;

FIG. 8 is a right side elevational view thereof; and,

FIG. 9 is a top edge elevational view thereof.

A human hand and stylus illustrated in broken lines are shown to illustrate environment only and form no part of the claimed design.
